UNITED STATES PATENT OFFICE

156,349

TOBACCO BAR

Joseph A. La Fond, Detroit, Mich.

Application May 10, 1948, Serial No. 146,259

Term of patent 3½ years

(Cl. D85—2)

To all whom it may concern:

Be it known that I, Joseph A. La Fond, a citizen of the United States, residing at Detroit, in the county of Wayne and State of Michigan, have invented a new, original, and ornamental Design for a Tobacco Bar, for which the following is a specification, reference being had to the accompanying drawing, forming part thereof, in which:

Fig. 1 is a perspective view of a tobacco bar showing my new design; and

Fig. 2 is a side elevational view thereof.

The side of the tobacco bar not shown is substantially identical with the side thereof which is shown in Fig. 2.

I claim:

The ornamental design for a tobacco bar, substantially as shown and described.

JOSEPH A. LA FOND.
